UNITED STATES PATENT OFFICE.

MARION W. PITNER, OF CHICAGO, ILLINOIS.

BURNER.

No. 872,846.

Specification of Letters Patent.

Patented Dec. 8, 1907.

Application filed March 26, 1906. Serial No. 308,100.

To all whom it may concern:

Be it known that I, MARION W. PITNER, a citizen of the United States, residing at Chicago, in the county of Cook and State of Illinois, have invented new and useful Improvements in Burners, of which the following is a specification.

This invention relates to burners of the type employed for burning gasolene or other hydrocarbon oil vapor, and is directed especially to the means for supporting the mantle on the burner and to the devices for sustaining the chimney and shade in place, and has for its objects to provide a simple, inexpensive device of this character wherein the shade and chimney supporting arms may be conveniently detached and interchanged for accommodating shades and chimneys of different sizes, and one wherein the mantle will be firmly supported upon the burner.

With these and other objects in view, the invention comprises the novel features of construction and combination of parts more fully hereinafter described.

In the accompanying drawings, there is illustrated a side elevation, partly in central, vertical section, of a burner embodying the invention.

Referring to the drawing, 1 designates the burner base composed of metal, as usual, and of tubular form, as shown, said base being provided at its upper end with an internal, marginal shoulder 2 on which the burner screen 3 is seated and marginally supported, there being, in accordance with the present invention, centrally disposed within the base 1 a substantially L-shaped supporting member or arm 4 having its vertical portion provided with a socket 5 and its horizontal portion terminally fitted in an opening 6 formed therefor in the wall of the base 1, there being formed at the upper end of the member a shoulder 7 on which the screen 3 rests and by which it is supported at its center, while seated at its lower end in the socket 5 is a vertical mantle supporting post or standard 8 having its upper end appropriately engaged with the upper end of the mantle 9, the lower end of which in closes the upper end of the burner base 1, as usual.

The burner base 1 is provided with a plurality of transverse internally threaded openings 10 to receive the lower screw-threaded ends 11 of shade supporting arms

12 formed for engagement at their upper ends with a shade 13 and curved inwardly between their ends, as shown, for engagement with the lower portion of a chimney 14, which is securely clamped between the arms 12, it being noted in this connection that the arms 12 may be readily detached from the base 1 to permit interchangeability of the arms for the accommodation of chimneys and shades of varying sizes, and furthermore, that the arms will while affording ample support for the glassware offer practically no obstruction to the air passing into the lower end of the chimney for feeding the burner.

It may be mentioned that in the operation of hydrocarbon vapor burners the mantle becomes highly heated and an excessive amount of heat is radiated therefrom, which necessitates the employment of comparatively large chimneys for permitting the free passage of a sufficient amount of air between the mantle and chimney to properly cool and prevent breakage of the latter, the sizes of the chimneys employed being varied to accord with the size of the mantles and in accordance with other varying conditions, provision for which contingencies is made by adapting the arms 12 to be interchanged in accordance with my invention, and as above described. Furthermore, in devices of this class, it has been found that where metal supporting posts for the mantles are employed the heat radiated produces an excessive expansion and contraction of the post, thus causing an objectionable movement of the mantle resulting in breakage of the latter. An attempt has been made to obviate this objection by employing magnesia center supports for the mantles, the burner being provided with a socket carried by the burner screen to receive the lower end of the post, this method being objectionable, however, to the extent that the weight of the post and mantle on the screen when heated causes the screen to sag and permit lateral movement of the post, thereby throwing the lower end of the mantle into contact with the burner and resulting in the mantle being broken. Under my improved device this objection is wholly overcome and not only is the center post and mantle maintained rigidly in proper position by means of the socket member 4, but the screen 3 is also supported at its center by the latter, thus prolonging the life of

the screen and entirely obviating damage to the mantle through movement of the center post.

Having thus described my invention, what I claim is:

1. In a device of the class described, a tubular burner base, a burner screen removably positioned thereon, a supporting member positioned wholly within and attached to the base, said member being formed for engagement with and to centrally support the screen and permit the latter to be removable from the member and having a socket to receive the lower end of a mantle supporting post.
2. In a device of the class described, a tubular burner base, an L-shaped supporting member disposed wholly within and attached at its lower end to the base, and having its upper end supported free of the base and a screen positioned at the upper end of the latter and centrally engaged with and supported by said member, the member being adapted for engagement with the lower end of a mantle supporting post.
3. In a device of the class described, a tubular burner base, a supporting member permanently disposed wholly within and attached to the base, said member being provided at its upper end with a bearing shoulder, and a screen positioned in the upper end of the burner base and loosely and removably resting at its center upon said shoulder, the supporting member being formed for engagement with a mantle-supporting post.
4. In a mantle burner, the combination of

a tubular base, a supporting member arranged within the base and extending vertically and provided with a vertical socket at its upper end, means for permanently attaching the bottom of the member to the base, a mantle supporting post held in an upright position solely by having its lower end removably resting in the socket of the member, and a removable screen supported loosely on the base and having an opening for receiving the member and post.

5. In a mantle burner, the combination of a tubular base provided with an internal shoulder disposed inwardly from its upper end, a central supporting member provided with an external shoulder and having a vertically extending socket, means for attaching the lower end of the member to the base, a mantle supporting post removably engaged in the socket, and a screen in the form of a disk set into the upper end of the base and resting on the internal shoulder of the latter and provided with an opening for receiving the upper end of the member and bearing on the shoulder of the latter, the disk coöperating with the said means for holding the member in fixed position so that the mantle supporting post will be maintained vertical.

In testimony whereof, I affix my signature in presence of two witnesses.

MARION W. PITNER.
